UNITED STATES PATENT OFFICE

SYDNEY G. SILBERSTEIN, OF BROOKLYN, NEW YORK

SHADOW-BOX CONSTRUCTION

Application filed August 27, 1930. Serial No. 478,139.

This invention relates to display devices and particularly to shadow box structures.

One object of the invention is to provide an improved collapsible cardboard display device having features of construction to reduce the cost of the device and render the same rugged, reliable and efficient in operation.

Another object of the invention is the provision of an improved shadow box with reference to the light supporting means as an element of a collapsible cardboard box structure.

Other objects and advantages of the invention will become apparent as the specification proceeds.

With the aforesaid objects in view, the invention consists in the novel combinations and arrangements of parts hereinafter described in their preferred embodiments, pointed out in the subjoined claims, and illustrated on the annexed drawing, wherein like parts are designated by the same reference characters throughout the several views.

In the drawings:

Figure 1 is a view in front elevation of a device embodying the invention.

Fig. 2 is a view in side elevation of same.

Fig. 3 is a top plan view of the device.

Fig. 4 is a vertical sectional view taken on the line 4-4 of Fig. 1.

Fig. 5 is a horizontal sectional view taken on line 5-5 of Fig. 1.

Fig. 6 is a plan view of a blank for the rear part of the device.

Fig. 7 is a plan view of a blank for the front part of the device.

Fig. 8 is a top plan view of the device corresponding to Fig. 3, in collapsing position and with the light bulb removed.

Fig. 9 is a view in side elevation of the device in collapsing position.

The advantages of the invention as here outlined are best realized when all of its features and instrumentalities are combined in one and the same structure, but, useful devices may be produced embodying less than the whole.

It will be obvious to those skilled in the art to which this invention appertains, that the

same may be incorporated in several different constructions. The accompanying drawing, therefore, is submitted merely as showing the preferred exemplification of the invention.

Referring in detail to the drawing, 10 denotes a device embodying the invention. The same includes a box structure made preferably of cardboard and including a front element 11 and a rear element 12. The front element includes a plane front wall 13 having a relatively large opening 14 of any suitable design, the opening being spaced from the edges of said wall. The upper portion of the front wall may have indicia forming openings 15 cut therein, and preferably backed by a translucent sheet of material 16 secured or glued to the rear side of said front wall. At the bottom of the display opening 14 may be provided a flap 17 integral with the front wall and adapted to extend rearward. This flap 17 may constitute a bottom wall, and may include a supporting tongue 18 coacting as hereinafter described.

The rear element 12 may include a rear wall 19, and relatively vertical side walls 20 integral therewith. The latter may be formed with marginal flanges 21 secured to the front wall 13 by small nails or adhesive as may be desired. Extending centrally, longitudinally of the side walls are score lines 22 whereby the side walls may be collapsed. At the bottom portion of the rear wall is a slit 23 and a downward projecting locking tongue 24 resiliently acting to close said slit, so that, on inserting the supporting tongue 18 into the slit, the locking tongue bears thereon to detachably and yet reliably engage the former in the slit.

At the upper part of the rear wall 19 is a flap 25 preferably integral with the same, although it may also be separate and engaged therewith. This flap 25 forms a top wall, and it may be provided with marginal flanges 26, 27, the former being extended upward and adapted to abut the front wall, and the latter being slotted at 28, providing a central flaplet 29. Thus the upper edge portions of the side walls 20 are engageable in said slits, with the flaplets disposed, for instance, outside of the box structure and the rest of the flanges

inside thereof. As the slits 28 are on opposite sides of the crease lines, a re-enforcement is obtained for the side walls 20 to prevent collapse thereof. An opening 29a in each side wall may coact with the corresponding flap-
5 let.

Any suitable source of light 30 may be disposed in the upper part of the box structure. For example, the top wall 25 may have an
10 opening 31 in which the socket 32 of the lamp is detachably fitted and supported, with the lamp in relative proximity to the indicia 15 to illuminate the same.

If an article supporting means 33 is to be
15 utilized, the same is preferably disposed within the box, and so as to support the article therein to be partially illuminated by light from the lamp 30. The said supporting means may be made of cardboard and col-
20 lapsible, and it may be detachably secured in position by downward extending tongues 34 received in openings or slots 35 in the bottom wall of the box structure. The means 33 may be made of one or more pieces, and col-
25 lapse thereof may be provided by fold lines 36.

The box structure may be conveniently made of two blanks 37, 38 corresponding to said rear and front elements, so that the device may be inexpensively produced.

30 In setting up the device, the side walls 20 are straightened out and the top and bottom walls or flaps engaged as shown in Fig. 4. Then the lamp and the article supporting means are mounted. To collapse the device,
35 the latter are removed, then the top and bottom walls 25 and 17 are swung upward into planes parallel to the front and rear walls as in Fig. 8, whereupon the side walls 20 are collapsible, so that the device may be brought
40 into perfectly flat position. Similarly the supporting means 33 may be made flat so that the entire device can be compactly and conveniently stored and shipped.

It will be appreciated that various changes
45 and modifications may be made in the device as shown in the drawing, and that the same is submitted in an illustrative and not in a limiting sense, the scope of the invention being defined in the following claims.

50 I claim:

1. A collapsible cardboard device includ-
55 ing front and rear vertical wall structures, each consisting of a single piece of material, the front structure having an opening and a flap at the bottom of said opening, the rear structure having a top flap and narrow side wall portions, said structures being secured together, said flaps having detachable en-
60 gagement with the respective opposing wall structures to form a box-like arrangement with said side walls, said side walls being longitudinally creased whereby the device
65 can be collapsed in the detached position of said flaps.

65 2. A collapsible cardboard display device

including a plane front wall having a relatively large opening spaced from the side edges thereof and an integral flap at the bottom of said opening, said flaps being adapted to be folded to extend rearward of the plane
70 of said wall, an element of box-like form, having a rear wall and integral side walls, the latter being permanently engaged with the said front wall at the sides of said opening, said rear wall having means for detach-
75 ably engaging said flap and supporting the same to provide a bottom wall, said rear wall having a movable flap at the top thereof to form a top wall, said side walls having longitudinal scored lines whereby said side walls may be collapsed with the flaps extending substantially parallelly to said front and rear walls.

3. A collapsible cardboard display device including a plane front wall having a relatively large opening spaced from the side edges thereof and an integral flap at the bottom of said opening, said flap being adapted to be folded to extend rearward of the plane
80 of said wall, an element of box-like form, hav-
85 ing a rear wall and integral side walls, perma-
nently engaged with said front wall at the sides of said opening, said flap having a tongue, and said rear wall having a slit and a downward extending tongue tending to close
90 said slit, the first tongue being received in the slit and detachably engaged by the second tongue, whereby said flap is reliably carried to provide a bottom supporting wall, said
95 rear wall having a movable flap at the top thereof to form a top wall, said side walls having longitudinal scored lines whereby said side walls may be collapsed with the flaps extending substantially parallelly to said front and rear walls.

4. A collapsible cardboard display device including a plane front wall having a relatively large opening spaced from the side edges thereof and an integral flap at the bottom of said opening, said flap being adapted to be folded to extend rearward of the plane
100 of said wall, an element of box-like form, having a rear wall and integral side walls, permanently engaged with said front wall at the sides of said opening, said flap having a tongue, and said rear wall having a slit and a downward extending tongue tending to close
105 said slit, the first tongue being received in the slit and detachably engaged by the second tongue, whereby said flap is reliably carried to provide a bottom supporting wall, said
110 rear wall having a movable flap at the top thereof to form a top wall, said side walls having longitudinal scored lines whereby said side walls may be collapsed with the flaps extending substantially parallelly to said front and rear walls.

115 5. A collapsible cardboard display device

120 125 130

5. A device as set forth in claim 3, including a folded collapsible table means located within said walls, said table means having downward extending tongues, said bottom flap having slots to receive said tongues, whereby the table means is detachably engaged.

6. A collapsible cardboard display device including a plane front wall having a relatively large opening spaced from the side edges thereof and an integral flap at the bottom of said opening, said flap being adapted to be folded to extend rearward of the plane of said wall, an element of box-like form, having a rear wall and integral side walls, permanently engaged with said front wall at the sides of said opening, said flap having a tongue, and said rear wall having a slit and a downward extending tongue tending to close 20 said slit, the first tongue being received in the slit and detachably engaged by the second tongue, whereby said flap is reliably carried to provide a bottom supporting wall, said rear wall having a movable flap at the top 25 thereof to form a top wall, said side walls having longitudinal scored lines whereby said side walls may be collapsed with the flaps extending substantially parallelly to said front and rear walls, said top flap having a movable abutment relation with said front wall in the top wall position of the former, whereby 30 collapse of the side walls is prevented.

7. A display device including a cardboard box having side walls provided with score lines, and the top and bottom walls being movable for collapsing the box along said score lines, the front wall of the box having indicia, and a source of light supported at the top of the box to illuminate the said indicia, 40 said top wall having slotted flanges to detachably engage the side walls in said slits with the slits disposed on opposite sides of the score lines to prevent collapse of the side walls and support the top wall thereon.

45 In testimony whereof I affix my signature.
SYDNEY G. SILBERSTEIN.
